MICROTOME KNIFE STROPPERS

Henry L. Ettman, Clayton, Mo.

Application March 28, 1957, Serial No. 649,129

3 Claims. (Cl. 51—102)

This invention relates in general to grinding, and more particularly, to a stropping wheel for microtome knives.

For the constant, efficient operation of microtomes, in hospitals, laboratories, and clinics, for sectioning of prepared tissue, as frozen or celloidin or paraffin-mounted, it is imperative that the knives therefor be maintained in a state of highly refined sharpness requisite for slicing sections having a thickness in the order of five microns or less. Heretofore, after a microtome knife had been ground it had been customary to subject same to manual stroking across an elongated leather strop to remove the "burr" or "wire" at the edge. This stropping or honing operation, which is substantially identical to the widely practiced domestic procedure for sharpening a straight razor for shaving, entails the use of a device for supporting at its ends a length of horizontally presented leather or related material so that an operator may by hand move the microtome knife thereacross reciprocatingly until the desired edge has been attained. However, such generally accepted hand stropping has quite understandably numerous disadvantages, among which is primarily a lack of uniformity in the stropped edge, with consequent want of uniformity in thickness of sections severed thereby. Since such operation is performed by hand the proficiency and skill of the individual will relate directly to the quality of fineness of the edge, and furthermore, there has been conclusively shown that hand stropping is effective only where the grain size of the abrasive incorporated in the leather falls within a substantially narrow range of relatively large size particles. Hence, fine abrasives so necessary for finishing the edge for cutting sections of marked thinness are not effectively used in a hand stropper.

In view of the required developed skill of the individual doing the stropping, hospitals, laboratories, and the like, have of necessity caused their microtome knives to be periodically transferred to some agency engaged in the microtome knife stropping service with the attendant costliness therefor.

Therefore, it is an object of the present invention to provide a motor driven knife stropping device capable of reliably and consistently applying an edge of maximum refinement and uniformity to microtome knives, skin grafting knives, and the like, and the operation of which does not require skilled personnel.

It is another object of the present invention to provide a microtome knife stroppler incorporating a motor driven wheel of predetermined diameter for effecting substantially flat abutment thereon of the edge portion of the knife to be stropped.

It is a further object of the present invention to provide a microtome knife stroppler adapted for operation within a predetermined speed range correlated to the range of grain size of abrasives incorporated in the stroppler whereby an extensive range of grain size abrasives may be effectively utilized for obtaining uniform cutting edges on microtome knives heretofore unattainable by hand stropping.

2

It is an additional object of the present invention to provide a microtome knife stroppler which is durable in operation; which is economical in production; and which may be speedily and efficiently operated so as to conveniently assure prompt readiness for use of microtome knives.

These and other detailed objects are obtained by the structures illustrated in the accompanying drawing, in which—

10 Figure 1 is a perspective view of a microtome knife stroppler constructed in accordance with and embodying the present invention.

Figure 2 is a vertical transverse section taken on the line 2—2 of Figure 1.

15 Figure 3 is a vertical transverse section taken on the line 3—3 of Figure 1.

Figure 4 is an enlarged detail illustrating the contact between the wheel and the knife to be stropped thereby.

Referring now by reference characters to drawing, A 20 designates a microtome knife stropping machine incorporating a rectangular housing 1 having end walls 2, 2', side walls 3, 3', a bottom wall 4, and being open in its upper portion as at 5 except for an inturned marginal flange 6. Extending through tapped openings in flange 6 at the corners of housing 1 are fixed screws 7, the upper ends thereof being threaded through aligned openings in a top closure plate 8, and being engaged by cap nuts 7'. Provided upon each screw 7 between flange 6 and plate 8 is an adjusting collar 9, upon selected operation of which the disposition 30 of top plate 8 with respect to housing 1 may be altered for purposes presently appearing. Thus, for example, collars 9 on an adjacent pair of screws 7 may be adjusted relatively to the remaining collars so as to cause the top plate to be horizontally inclined, or, manifestly, all collars 9 may be regulated for raising or lowering of said plate 8 within the range provided by the available length of screw 7.

Disposed within housing 1 is a prime mover or motor M connected to a source of power external of housing 40 1 as by leads indicated at 10; there being an operating switch 11 connected to said motor and positioned for convenient presentation of its toggle arm upon the outer surface of end wall 2'. Motor M comprises a drive shaft 12 having mounted on its outer end a pulley 13 about which is trained a drive belt 14; in its opposite end portions said belt is disposed about a relatively enlarged pulley 15 carried on the end of an idler shaft 16 journaled in a bearing 17 disposed on the interior surface of end wall 2. Idler shaft 16, between pulley 14 and bearing 17, mounts a stropping wheel 18, the upper portion of which extends 50 upwardly through the open upper end 5 of housing 1 and through a small, slot-like opening 19 formed in closure plate 8; said opening 19 being slightly greater than the thickness of wheel 18.

Secured or otherwise fixed on the upper surface of 55 closure plate 8 is a pair of spaced apart guide members 20, 20' cooperating to form a way for a slide 21 which is centrally slotted, as at 22, for extension therethrough of a screw 23 rigid in plate 8 and having a retaining wing nut 24 threaded on its upper projecting end so that upon 60 loosening of wing nut 24 slide 21 is freed for movement relatively between members 20, 20' and upon tightening of said nut 24 said slide 21 will be maintained in selected position. Guide members 20, 20' are so presented as to define the path of movement of slide 21 along an axis substantially tangentially aligned with, or parallel to the tangent of, the upper portion of wheel 18 extending through opening 19.

70 Mounted on the end of slide 21, perpendicular thereto, and proximate wheel 18, is an elongated microtome knife holder 25 extending almost from end to end of closure plate 8. Said holder 25 is of a generally stepped

configuration having a lower step or knife support ledge 25' planar-wise parallel to closure plate 8, and a riser-like abutment 25". As the thickness of wheel 18 is less than the length of microtome knives to be serviced by machine A, a microtome knife must, perforce, be moved by the operator along support ledge 25' so as to present the entire edge portion of the knife to the wheel 18. In the drawing K indicates a microtome knife being provided with the conventional back 26 which may be retained upon the knife during stropping.

Indented or otherwise inscribed upon the upper surface of closure plate A spaced from knife holder 25 and axially parallel therewith is a guide line 27 so related to stropping wheel 18 as to be aligned with the remote terminus of the "flat" curve (to be described) at the extreme projecting portion thereof. Thus, knife holder 25 will be adjustedly disposed so that the edge of a knife to be stropped, and supported thereon, will be in alignment with guide line 27 by which condition proper address of the knife K to wheel 18 is certain.

In the stropping of microtome knives it is critical that the cutting edge portion thereof be disposed flatwise upon the strop, just as with the typical hand strops heretofore used, in order to attain substantial uniformity of striations in such edge. Without such flat presentation, the resulting edge will be irregular and hence unproductive in usage of sections of uniform thickness, and obviously unfit for providing that degree of thinness in sections so vital for innumerable analyses. This vital contact between knife and strop had up to the present been considered unattainable by any agency other than the well-known elongated razor-type strop and accounts for the continued adherence to the utilization of the same. However, it has been found that a wheel having a diameter of at least eight inches will provide in its circumference a curve of such angle as to be substantially coincident in extent with the edge portion of the microtome knives, and substantially coincident with its chord so as to provide what might be termed a "flat" curve, and thereby assure the critical engagement with the knife over the necessary surface thereof for attaining the requisite optically determined stropped edge. Thus, Figure 4 of the drawing illustrates this contact between the face of wheel 18 and the edge of knife K. The importance of this feature will be apparent when it is recognized that heretofore the proper presentation of microtome knives to strops was attained through the developed proficiency and skill of the operator and, obviously, the interjection of human error was a constantly present factor. With the present invention, the proper engagement will at all times be reliably effected so that the stropping operation will unfailingly produce the desired results.

The angle of the bevel of the cutting edge on knife K may through the operation of machine A be of any desired degree, with the relationship between closure plate 8 and wheel 18 being determinative, as by the selected positioning of closure plate 8 through use of collars 9. Thus, as closure plate 8 together with knife holder 25 thereon, is relatively raised, a reduced portion of wheel 18 will project thereabove, through opening 19, so that a somewhat steep bevel may be obtained, while conversely upon lowering of closure plate 8 a relatively shallow bevel will result. But, regardless of such adjusting the flatwise engagement between wheel 18 and knife K will be maintained. It will be observed that the adjustability of knife holder 25 through operation of slide 21 will permit machine A to accommodate microtome knives of varying sizes.

The stropping operation is easily accomplished by use of machine A, as the user after having adjusted knife holder 25 with respect to guide line 27 for the particular knife being serviced, and positioned closure plate 8 for the desired degree of bevel, need only slide knife K along step 25' so as to present one surface of the edge portion,

to wheel 18, and then to turn knife K over to present the opposite surface of the cutting edge for stropping.

As will now be developed, the speed of rotation of wheel 18 and the range of grain size of abrasives utilized therewith has been found to fall within certain relatively well defined ranges, with a definite correlation therebetween.

With respect to the angular velocity or speed of grinding wheel 18 it has been found that an average such as 10 to provide a thousand feet per minute of wheel surface will provide the best results. Thus, a speed of between 400 and 700 revolutions per minute for use with diamond base abrasives within the range of 600 to 25,000 mesh, is competent to provide the maximum effectiveness. It 15 has been found that within a speed range of 700 to 1200 revolutions per minute an effective abrasive is alumina which is slightly less hard than diamonds and which in this instance would preferably be from .1 to .3 microns. Other abrasives, such as silicon carbide, fused Al_2O_3 , e.g. 20 "Alundin" (being a trademark of the Norton Co. for fused alumina) up to 1,000 mesh and between a speed of 800 and 2000 revolutions per minute have been found equally effective for the stropping operation herein.

It must be recognized that the drive connection between motor M and wheel 18 may be easily controlled by any well known expedients so as to provide the desired speed for the particular grain size of abrasive on wheel 18.

Stropping wheels of the type incorporated in the present invention may be formed of a plywood base or any other like durable material with the periphery thereof covered with leather, such as even grained cordovan or other well known material capable of receiving abrasives. The abrasives utilized with wheel 18 are preferably of a diamond base but may be of silicon carbide or the like, and, as suggested above, should have a mesh size falling within the range of 600 to 25,000. Also, abrasives within this range may vary in hardness within a comparable range.

Heretofore with hand strops there was a definite limitation on the fineness of the abrasives which could be effectively utilized therewith, such abrasives defining a relatively narrow range of about 600 to 1200 mesh. Abrasives exceeding that range in fineness could not be practically utilized as the knife would have had to be moved relatively more rapidly across the strop than could be reliably effected by hand. With the present invention grain sizes ranging in fineness up to 25,000 mesh may be incorporated in wheel 18 as the latter may be rotated at speeds necessary for use of abrasives resulting in edges of extreme fineness, capable of severing sections of a degree of thinness hitherto beyond the competency of microtome knives manually stropped. The speed of rotation of wheel 18 will be regulated within the stated range for correspondence to the particular grain size, as the finer the grain the greater the speed.

The operation of machine A is such as to assure that the cutting edge upon the knife being stropped will have a uniformity as to extent of striations formed jointly therein by the initial grinding and subsequent stropping operations, with the result that sections cut thereby will have a like uniformity of thickness. Hand stropped microtome knives consistently have, by dint of human error implicit in the hand operation, a variation in sharpness, as the desired uniformity in the edge striations is necessarily lacking, so that sections cut thereby are similarly devoid of uniformity in thickness and have, what might be described as, a waxy effect. These imperfections had up to the present time been reluctantly accepted as an unvarying condition. Such lack of uniformity by hand stropping was customarily aggravated when relatively hard, coarse abrasives were utilized, such as needed in stropping a knife for the cutting of reasonably hard dense sections.

Thus, in view of the foregoing it is seen that the ma-

chine of the present invention has been designed to provide the necessary relationship between the stropping surface and the blade being serviced, and also to operate at such speeds as to render it capable of incorporating abrasives falling within a very broad range of size as well as density so that a controlled cutting edge obtained by use of machine A; which edge shall be of the utmost refinement and adapted both as to thickness of section as well as hardness of the same.

As shown hereinabove, machine A is so devised as to operate in a consistently reliable manner; which does not necessitate the services of highly skilled and trained individuals but which, by the nature of its constituent parts and the specific relationship thereof, will consistently assure that the requisite highly finished cutting edge will at all times be provided.

Although stropping wheels having a diameter of eight inches have been found competent to effect the desired "flat" engagement with the cutting edge of microtome knives of widely used size, it is to be recognized that if machine A is to be utilized with knives of relatively increased size the particular stropping wheel will accordingly necessarily be of greater diameter so as to present a curve of requisite "flatness" for the particular extent of cutting portion to be serviced. A wheel of 8 inches as shown herein has been found to be of generally wide and practical use, but wheels of greater size are within the comprehension of this invention so as to achieve the proper relationship with larger knives.

It should be understood that changes and modifications in the formation, construction, arrangement, and combination of the several parts of the microtome knife stropper may be made and substituted for these herein shown and described without departing from the nature and principle of my invention.

Having thus described my invention, what I claim and desire to secure by Letters Patent is:

1. In a stropping machine for microtome knives, the improvement comprising a wheel having a diameter of no less than eight inches whereby the circumferential curve of contact with a microtome knife to be stropped will be substantially coincident in extent with the edge portion of the knife and with the chord of such curve, means for rotating said wheel in a direction away from the knife edge portion, a peripheral covering of cordovan leather for said wheel, diamond-base abrasives embedded within said cordovan leather peripheral covering and having a fineness within the range of 14,000 to 25,000 mesh, said wheel being designed for rotation within the range of 750 to 1,000 revolutions per minute, with the velocity within such range being inversely proportional to the mesh size of the abrasive.

- 5 2. A stropping machine comprising a casing having parallel side and end walls and a bottom wall, a closure plate provided on the upper end of said casing and having an aperture therein, a stropping wheel mounted for rotation within said casing having a peripheral portion projecting through the aperture in said closure plate, said wheel having a diameter of about 8 inches whereby the circumferential curve of contact with a microtome knife to be stropped will be substantially coincident in extent with the edge portion of the knife and with the chord of such curve, a peripheral covering of cordovan leather provided on said wheel, diamond-base abrasives imbedded within said cordovan leather peripheral covering and having a fineness within the range of 14,000 to 25,000 mesh, spaced guideways provided on the upper surface of said closure plate, a slide body disposed within said guideways for slideable movement therealong, the axis of said slide body being coincident with a line tangential to the projecting portion of said wheel, a microtome knife holder mounted on the end portion of said slide body proximate the projecting portion of said wheel and being axially normal to said slide body, said holder having a support ledge extending from end to end thereof on its face confronting said wheel, an abutment surface extending upwardly from said ledge and being coextensive therewith and means provided in said casing for effecting rotation of said wheel in a direction away from the knife edge portions.
- 10 3. A microtome stropping machine as described in claim 2 wherein means are provided for maintaining said slide body in selected position with respect to the guideways, adjustment means being provided for regulating the height of the closure plate with respect to the upper edge of the casing, and wherein the support ledge of the knife holder is in planar parallel relation to the upper surface of the closure plate.
